UNITED STATES PATENT OFFICE.

ARTHUR VENNELL COSTER, OF MARPLE, ENGLAND.

HYDRO-EXPLOSIVE MOTOR

1,055,880.

Specification of Letters Patent. Patented Mar. 11, 1913.

Application filed September 28, 1912. Serial No. 722,833.

To all whom it may concern:

Be it known that I, ARTHUR VENNELL COSTER, a subject of the King of Great Britain and Ireland, and resident of Marple, in the county of Derby, England, have invented certain new and useful Improvements in Hydro-Explosive Motors, of which the following is a specification.

This invention relates to improvements in that class of motor in which successive explosions are utilized to propel or project a plug of water at frequent intervals through a turbine to drive it, or to propel or project for the same purpose successive and separate plugs of water. Such a plug or plugs will be hereinafter generally referred to as successive plugs. In carrying my invention into effect in such a motor I dispense altogether with the mechanically operated valve or the like which has hitherto been known in combination with the explosion chamber to control the propulsion of the water therefrom to the turbine, and I so arrange and dispose the water conduits in connection with the turbine and the explosion chambers or chamber that a propelled plug of water by its own kinetic energy on its way to the turbine exhausts and draws after it the gases by which it has been propelled, and also by its kinetic energy, on its direct return to the explosion chamber from the turbine, directly effects the compression of the explosive charge by which it will next be propelled. The exhaustion of the spent gases may itself induce a fresh explosive mixture into the explosion chamber, or such fresh charge may be otherwise supplied. The products of combustion which follow the propelled water escape without the necessity of employing an exhaust valve in the combustion chamber.

The accompanying drawings illustrate diagrammatically one form of motor constructed according to this invention and will now be referred to.

Figure 1 illustrates the motor in vertical section and in elevation. Fig. 2 illustrates it in plan with part in section.

a is the explosion chamber in which the charge of gaseous mixture is exploded, said chamber being provided with the usual electrical igniting means *x*, *b* is the turbine, *c* is a pipe leading from the explosion chamber to the turbine, *d* is a pipe leading from the turbine back to the explosion chamber through part of the pipe, *e* is a non-

return valve controlled by a spring *e'* situated at the junction of the pipes *d* and *c*. This valve will permit flow from the pipe *d* into the pipe *c* but not in the reverse direction. The pipe *c* is bent to form an elbow at its lowest part as shown and this elbow is filled when the engine is not running (and intermittently when the engine is running) by water to the level indicated by *f*. 60

When the turbine is at rest the water level is as indicated in Fig. 1. The explosion chamber *a* and that part of the pipe *c* above the level of the liquid in the left hand end of the pipe is filled by an explosive 70 gaseous charge or mixture which may, for example, be pumped or otherwise forced in. The gaseous charge is now ignited and the pressure set up propels or projects the water contained in the pipe *c* past the closed non-return valve *e* to and through the turbine and its casing and to the pipe *d*. The quantity of water employed, and the areas and forms of the pipes, are such that the water effects and permits and possesses sufficient 75 kinetic energy to effect the operations now to be described. The products of combustion follow the tail end of the plug of water to, and to a large extent through the turbine, and a degree of vacuum is set up in 80 the explosion chamber and the pipe *c* which results in a gaseous mixture being drawn into the explosion chamber and the pipe through suitable induction valves situated 85 in the combustion chamber. The appliances 90 by which the explosive charge is fed or led to the explosion chamber are preferably so formed or disposed or operated that air enters the explosion chamber first and directly follows the products of combustion which 95 themselves are following the water. At about the moment the induced charge following the products of combustion is reaching the valve *e* the head of the plug of water coming from the turbine through the 100 pipe *d* also reaches the same valve, moves it inward, and enters the pipe *c*, stopping the motion of the induced charge and driving such charge to the explosion chamber and compressing it. The valve *e* may be so loaded that it opens or commences to open before the head of the plug of water reaches it, as a result of the partial vacuum set up in the pipe *c*. When the water has fully re-entered the pipe and momentarily occupies 110 and passes through the approximate position in which it is shown in Fig. 1, the valve 105

5 *e* again closes. The water however continues its movement to the left, the left hand end of the plug even rising after the first few explosions to the level indicated at *f*' and thus further compresses the gaseous charge in the explosion chamber. The charge is then ignited and the described operation is repeated. The ignition is automatically effected as, for example, by and as a consequence of the closing of the valve *e*, a suitable part of which closes the electric circuit in which the sparking plug is placed.

10 The products of combustion which have followed the water through the turbine are led away in any suitable way. It will be seen that in the example illustrated the water is projected through the turbine wheel at a low level. The products of combustion at once rise in the turbine casing from 15 the water conducting trough or the like leading to pipe *d* on the delivery side of the wheel and may escape as desired. They may however be positively withdrawn as for example by the fan *g* mounted on the shaft 20 *g*' of the turbine wheel and discharging into the exhaust pipe *h*.

25 By the arrangement described it will be seen that the water reentering the pipe *c* from the turbine and continuing its passage 30 in the direction of the explosion chamber cuts off or traps the products of combustion which are following the tail of the plug of water and prevents them from returning to the combustion chamber.

35 In the motor I have illustrated I have shown a single explosion chamber only operating in conjunction with a turbine, but two or more separate explosion chambers each formed with its own pipes *c* and *d* may 40 direct water upon different parts of the same wheel. Also in the motor shown the water coming from the turbine wheel directly re-enters its own explosion chamber from which it has been propelled to and through 45 the turbine. With two or more explosion chambers and sets of pipes, however, the water coming from one explosion chamber to the turbine may be led from such turbine to the other or another explosion chamber 50 by suitable cross connecting pipes, and it will operate therein or in connection therewith in the manner already described in connection with the explosion chamber from which it has been projected.

55 To make up for the water wasted and lost by evaporation, leakage and splashing, and to keep the water at a low temperature, a water inlet valve may be arranged at a suitable part of the system so that a little water 60 is drawn into the system at each reciprocation of the water plug. The valve illustrated at *j* is spring controlled and opens to admit water from the tank *k* to the interior of the pipe *c* when the pressure in the latter 65 falls after an outward traverse of the water

70 plug. The valve *j* is of an area and is set to supply the required quantity of water. The flow and return pipes *c* and *d* should have as few bends or turns as possible, and give to and maintain the water in the straight 75 and direct flow and return described.

Although the motor has been described as with an induction flow of the gaseous explosion mixture set up directly by and as a consequence of the partial vacuum set up in the pipe *c*, I do not confine myself to such an induction of the explosive mixture. Such a mixture or its components may be supplied to the explosion chamber under suitable pressure, and the flow be controlled in any 80 convenient way, as, for instance, by the movement of the valve *e*. This valve when opening to admit water from the return pipe *d* to the pipe *c* may permit the inward flow of an explosive mixture to the explosion chamber, and cut off the supply of such mixture as it closes.

85 I do not confine myself to the wheel type of turbine shown in the drawings. Any other suitable form of water turbine may 90 equivalently or similarly have the pipes *c* and *d* combined with it.

95 The valve through which a charge of gaseous mixture can be admitted to the explosion chamber to start the motor as already described, may also be used during the running of the motor as an auxiliary valve which may be adjusted as desired for varying the richness of the mixture.

100 The power produced may be regulated by a governor driven from the turbine shaft and controlling either the quality or quantity of the gaseous mixture admitted to the explosion chamber, or the weight or velocity of the water discharged may be controlled 105 by gradually increasing or diminishing its volume through the opening or closing of the valve *j*.

110 The turbine is arranged to drive any desired machinery. It is shown in the drawings as being provided with a driving pulley *m*.

What I claim is:—

1. A motor comprising in combination an explosion chamber, a turbine, a pipe leading directly from the explosion chamber to the turbine, an elbow formed in said pipe at its lowermost portion adapted to contain a plug of water, a return pipe leading from said turbine to the first mentioned pipe, a non-return valve at the junction of said delivery and return pipes, means for exhausting the products of combustion from the turbine, and means for igniting the contents of the explosion chamber, substantially as described.

120 2. A motor comprising in combination an explosion chamber, provided with an electrical igniting means, a turbine, a pipe continuous with said explosion chamber leading 130

directly to said turbine, said pipe being curved in such manner as to form an elbow at its lowermost part for the retention of a plug of water, a return pipe leading from 5 said turbine to the first mentioned pipe at a point above the elbow and at the side remote from said explosion chamber, means for exhausting the products of combustion from said turbine, and means for renewing the

supply of water comprising the water plug, 10 substantially as described.

In witness whereof I have hereunto set my hand in the presence of two witnesses.

ARTHUR VENNELL COSTER.
